UNITED STATES PATENT OFFICE.

EDWARD C. LEACH, OF NORWALK, CONNECTICUT.

BOTTLE-STOPPER.

No. 851,990.

Specification of Letters Patent.

Patented April 30, 1907.

Application filed October 9, 1905. Renewed October 3, 1906. Serial No. 337,276.

To all whom it may concern:

Be it known that I, EDWARD C. LEACH, a citizen of the United States, residing at Norwalk, in the county of Fairfield and State of Connecticut, have invented a new and useful

5 Bottle-Stopper, of which the following is a specification.

This invention relates to a stopper which is particularly adapted to be applied to the 10 neck of a bottle containing a beverage or condiment, but it is useful for closing the mouth of a bottle containing any liquid.

The object of the invention is to provide a simple, cheap and cleanly stopper which may 15 be readily applied to or removed from the neck of any common bottle, and which can be easily manipulated for opening and tightly closing a bottle mouth of any ordinary size.

The embodiment of the invention which is 20 illustrated has a spring band which is adapted to clasp the neck of a bottle, a globular stopper which is adapted to close the mouth of the bottle, and spiral springs connecting the band and the stopper in such manner as to hold 25 the latter tightly to the mouth of the bottle.

Figure 1 of the accompanying drawings shows the neck of a bottle with the mouth closed by one of these stoppers. Fig. 2 shows a plan view of the same. Fig. 3 shows 30 a side view with the stopper rolled away from the mouth.

The band 1 is preferably made of a piece of spring wire formed into a circle which is smaller in diameter than the neck of the bottle to be clasped. The overlapping ends of 35 the wire are bent to form eyes 2 which may be grasped by the fingers for opening the band when it is applied to or removed from the bottle. Rubber tubing 3 is preferably

40 placed on the wire to protect it from the corrosive action of the salts and acids of any substance which may be placed in the bottle and to form a cushion which will insure a firm and close grip on the neck of the bottle.

45 The stopper 4 which is shown as globular may be formed of rubber, wood, metal or glass as desired. Extending through the center of the stopper is a bail 5. A spiral spring 6 connects each end of the bail to the 50 band. These springs have the requisite stiffness to draw the stopper tightly to a seat upon the mouth of the bottle.

The stopper is easily applied by opening the band and springing it about the neck of the bottle below the head or in a groove between the neck and the head. The tension of the wire and the flexibility of the rubber which covers the wire causes the band to tightly grip the neck and hold in place. The stopper is readily located in the mouth of the 6c bottle by rolling it over the edge, the globular form providing sufficient body to be easily grasped by the fingers or pushed by the thumb and insure a tight seating of the stopper on the mouth.

65 An opening 7 may be made diametrically through the stopper and the stopper may be rotated on the bail so that the opening will come in line with the mouth allowing liquid to be turned out of the bottle through this 70 opening. The stopper is easily rotated so that the opening is away from the mouth, then nothing can be poured out.

This stopper can be made ornamental and can be quickly applied to the neck of any 75 bottle of ordinary dimension and the stopper will tightly close a mouth of any common size. It can be easily removed if solid, or rotated if perforated, to allow liquid to be 80 poured out of the bottle and then quickly adjusted so as to close the mouth. When the bottle is turned away from the mouth it is held up by the springs so as not to interfere with the flow of liquid. This stopper is particularly desirable for use in connection 85 with bottles which have had their permanent seals broken and it is desired to close the bottles in such manner that they can be opened at intervals and yet kept closed sufficiently tight to prevent deterioration of the 90 contained liquid.

The invention claimed is:—

A bottle stopper consisting of a band formed of spring wire and rubber tubing, a globular stopper, a bail extending through 95 the center of the stopper, and spiral springs connecting the ends of the bail and the band, substantially as specified.

EDWARD C. LEACH.
